UNITED STATES PATENT OFFICE.

ANTON VOGT, OF RACINE, WISCONSIN, ASSIGNOR TO E. C. TECKTONIUS MANUFACTURING CO., OF RACINE, WISCONSIN, A CORPORATION OF WISCONSIN.

KILN.

1,153,980.

Specification of Letters Patent. Patented Sept. 21, 1915.

Application filed December 3, 1913. Serial No. 804,367.

To all whom it may concern:

Be it known that I, ANTON VOGT, a citizen of the United States, residing at Racine, in the county of Racine and State of Wisconsin, have invented certain new and useful improvements in Kilns, of which the following is a specification, reference being had to the accompanying drawing, forming a part thereof.

This invention relates more particularly to round, up and down draft kilns for burning brick, tile and other articles made of clay. Its main objects are to evenly distribute the heat throughout the kiln and to insure uniform burning of the ware in all parts of the kiln, adjacent to the wall and between the bags as well as in the center; to reduce the time of "water-smoking"; to prevent crushing and distorting the ware in the lower courses, and to avoid "whitewash" and "efflorescence" of the ware, thereby increasing the quantity and improving the quality of the finished product; to reduce the time required for firing and economize fuel; and generally to improve the construction and operation of kilns of this class, by creating a live draft from the start of the fires, thereby expelling the moisture more rapidly.

It consists in the construction, arrangement and combination of parts as herein-after particularly described and pointed out in the claims.

In the accompanying drawing like characters designate the same parts in the several figures.

Figure 1 is a vertical central section on the line 1—1, Figs. 2 and 4, of a kiln embodying the invention; Fig. 2 is a horizontal section of the kiln, a portion of the open work floor being removed to disclose the construction of the underlying flues; Fig. 3 is a vertical section on the line 3—3, Fig. 2, showing an auxiliary furnace for heating the stack or chimney and creating a strong draft therein from the time the fires are started; Fig. 4 is a central vertical section of the kiln on the line 4—4, Figs. 1 and 2; and Fig. 5 is a vertical section on the line 5—5, Fig. 2, through one of the furnace or fire holes and interior vertical flues located at intervals around the kiln.

The kiln comprises a substantially circular wall *a*, surmounted by an arched crown *b*, constructed of brick, the wall *a* being sur-

rounded and reinforced by metal bands *c*. On one side of the kiln the wall *a* is formed with a doorway *d*, as shown in Figs. 1 and 2, for charging the kiln and removing the burned product therefrom. It is also formed at intervals, as shown in Figs. 2 and 5, with fire openings or furnaces *e*, and with interior flues known as "bags", extending upwardly therefrom and opening at their upper ends into the upper part of the kiln. These fire openings or furnaces are provided, as shown in Fig. 5, with inwardly and downwardly inclined fuel supports *g*, each consisting of a metal frame and an imperforate lining of refractory material such as fire brick. The inclined fuel supports *g* rest loosely on cross bars spanning the fire openings and are removable to facilitate cleaning or repairing the furnaces as well as the fuel supports themselves. The bottom of the openings *e* and the flues *f*, forming the fire chambers and ash pits, are paved or provided with a layer of fire brick.

The arched crown *b* is formed with a central opening *j*, which is closed and sealed during the firing of the kiln, by a removable cover *k*, as shown in Fig. 1. A stack or chimney *l*, located at one side of and a short distance from the kiln, is constructed of brick with ventilated air spaces *m* in its walls, as shown in Figs. 1 and 2, these spaces communicating through openings *n* in the outer walls of the stack or chimney with the atmosphere. As shown, the chimney may be constructed with two or more independent flues *o*, for a number of kilns.

In the base of the kiln, preferably below the normal ground level, a radial arched flue *p* is formed, leading from the center of the kiln into the stack or chimney *l*. At its inner end this flue intersects or opens into a transverse flue *q*, extending diametrically across the base of the furnace and communicating at its ends with auxiliary furnaces *r*, as shown in Fig. 4. The furnaces *r* open at their outer ends into walled well holes *s*. Above and parallel with the radial flue *p*, a series of horizontal flues *t* is formed in the base of the furnace. These flues *t*, which are separated from one another by imperforate brick walls, are arranged parallel with the flue *p* and open into the upper part of the transverse flue *q*, which they cross. Another series of horizontal flues *u*, is formed in the base of the kiln above and

parallel with the flues *t* by open work brick walls through which they freely communicate with one another. Between the lower series of flues *t* and the upper series of flues 5 *u*, a false floor or brick deflecting partition *v*, is laid. This floor or partition is formed adjacent to the wall *a* of the kiln, with openings *w*, through which the lower and upper flues communicate with one another at their 10 outer ends. It is also formed in its central portion above and adjacent to the flue *q*, with a number of comparatively small openings *x*, through which the heated products of combustion from the kiln may pass from 15 the upper flues *u* in the central portion of the kiln more or less directly into the flue *q*.

Upon the walls between the upper flues *u*, is laid an open work floor *y*, constructed as shown, of bricks which have recesses formed 20 in one side thereof, and which when placed together, form vertical apertures opening into said flues. This floor *y* is preferably laid at about the normal level of the ground outside the kiln, the floor flues *t* and *u*, cross 25 flue *q* and the main flue *p*, leading from the cross flue to the stack, all being below the ground level.

Adjacent to the stack or chimney *l*, the flue *p* is formed with a man hole *z*, through 30 which access is had thereto for inspection, cleaning and repair. This man hole is normally closed by a cover *2*. A vertically sliding damper *3*, next to the stack or chimney, affords means for regulating the draft 35 through the entire kiln.

For warming the stack or chimney and starting a strong upward draft therein preparatory to firing the kiln, an auxiliary furnace *4* is connected through an opening 5 with each flue *o*, near the base of the chimney, as shown in Figs. 2 and 3.

In the operation of the kiln, the brick, tile or other articles to be burned having 45 been stacked on the floor *y*, and the doorway *d* closed by a suitable door (not shown) and sealed, fires are lighted in the auxiliary furnaces *r* at the ends of the flue *q* and in one of the furnaces *4*, which opens into the chimney flue *o* with which the flue *q* is connected by the main or radial flue *p*, the 50 damper or valve *3* being closed more or less, and the cover *k* removed from the opening *j* in the crown of the kiln. The heat generated in the furnaces *r* produces an up draft 55 through the floor flues *t* and *u* and the open work floor *y*, and thence through the kiln around the green ware stacked therein, the floor flues and floor and the lower courses of the ware being thus preliminarily heated, 60 and the moisture driven therefrom through the vent opening *j* in the top of the kiln. The fire in the auxiliary furnace *4* preliminarily heats or warms the walls of the chimney flue, inducing a strong upward draft 65 therein, and the preliminary heating of the

floor and floor flues of the kiln by the auxiliary furnaces *r* preparatory to the final burning of the ware in the kiln, materially shortens the "water-smoking" in the firing of the kiln, drives the moisture from the 70 ware, particularly in the lower courses nearest the fire, and prevents the crushing and distortion of the ware and also "whitewash" and "efflorescence" thereof by water-smoking. Fires are then started in the furnaces 75 *e*, the opening *j* in the crown of the kiln is closed and sealed, the outside openings into the auxiliary furnaces *r* and *4* are closed, and the damper *3* is opened. A strong down draft is thus produced through the open 80 work floor *y* and the floor flues *u* and *t*, passing outwardly through the flues *u* to the outer ends thereof, thence downwardly through the openings *w* next to the wall *a*, thence inwardly through the lower flues *t* 85 into the top of the transverse flue *q*, and thence through the radial flue *p* into the chimney flue *o*, the heat generated in the several furnaces *e*, passing upwardly therefrom through the flues or bags *f* into the 90 upper part of the kiln, being deflected downwardly by the arched roof *b*, and evenly distributed throughout the kiln. The deflection of the hot currents by the false floor or partition *v* outwardly toward the wall *a* of 95 the kiln, and their sinuous course through the floor flues, evenly and effectively distribute the heat, causing the ware at the sides as well as at the center of the kiln, to be thoroughly and uniformly burned, and materially shortening the time required for 100 burning and correspondingly reducing the consumption of fuel.

The distribution of heat in the kiln may be adjusted for different kinds of ware and 105 for varying conditions, by closing more or less of the openings *x* in the central portion of the false floor or partition *v*, so as to permit more or less of the hot currents or the heat to pass directly into the cross flue *q* 110 adjacent to the center of the kiln, instead of through the openings *w* next to the wall *a*. The draft through, and hence the heat in the entire kiln is easily controlled and regulated by the adjustment of the single flue 115 damper *3*.

Various changes in minor details of construction and arrangement of parts may be made without materially affecting the operation of the kiln and without departing from the principle and scope of the invention as defined in the following claims.

I claim:

1. A kiln comprising a substantially circular wall, surmounted by an arched top 120 and provided at intervals with fire openings and interior flues extending upwardly from said openings, a stack, a main radial flue leading from the center of the kiln to the stack, a cross flue intersecting the inner end

of the main flue, and extending therefrom to the circular wall on opposite sides thereof, a lower series of flues above and parallel with the main flue having imperforate side walls and opening into the top of the cross flue, a false floor laid over said series of flues, an upper series of flues above the false floor parallel with the lower flues with which they communicate at their outer ends through openings in the false floor next to the circular wall of the kiln, and an open-work floor laid over the upper series of flues and having its openings distributed throughout its entire area and communicating with the several flues next below it.

2. A kiln comprising a substantially circular wall surmounted by an arched top and provided at intervals with furnaces or fire openings and interior flues extending upwardly therefrom and opening into the upper part of the kiln, a stack at one side of the kiln, a radial flue leading from the central part of the kiln into the stack, a transverse flue extending diametrically across the kiln from side to side thereof and opening into the radial flue at its inner end, a lower series of flues having imperforate side walls extending across the kiln above and parallel with said radial flue and opening into the top of said transverse flue, an upper series of flues extending across the kiln above and parallel with those of the lower series and having open-work side walls through which they communicate with one another, a false floor or partition between said lower and upper series of flues having openings through which the upper flues communicate with lower flues at their ends next to the wall of the kiln, and an open-work floor over the upper series of flues having its openings distributed throughout its entire area and communicating with the several flues next below it.

3. A kiln comprising a circular wall surmounted by an arched crown and provided at intervals with furnaces or fire openings and interior flues leading upwardly therefrom into the upper part of the kiln, a stack at one side of the kiln, a radial flue leading from the central part of the kiln into the stack, a transverse flue extending entirely across the kiln and communicating with the inner end of the radial flue, a lower series of flues extending across the kiln above and parallel with said radial flue and opening

into the top of said transverse flue, an upper series of flues extending across the kiln above and parallel with those of the lower series, and having perforated side walls through which they communicate with one another, a false floor or partition between said lower and upper series of flues formed with openings through which they communicate with one another at their outer ends and adjacent to said transverse flue, and an open-work floor over the upper series of flues having its openings distributed throughout its entire area and communicating with the several flues below it.

4. A kiln comprising a circular wall surmounted by an arched crown and provided at intervals with furnaces and interior flues leading upwardly therefrom into the upper part of the kiln, a stack at one side of the kiln, a radial flue leading into said stack, a cross flue intersecting the radial flue at its inner end and provided at its outer ends with auxiliary furnaces, a lower series of flues above and parallel with the radial flue and opening into the upper part of the transverse flue, an upper series of flues parallel with said radial flue, a partition between the upper and lower series of flues formed with openings through which they communicate with one another at their outer ends, and an open-work floor over the upper series of flues.

5. A kiln comprising a wall surmounted by an arched crown and provided at intervals with fire openings and interior flues leading upwardly from said openings into the upper part of the kiln, a stack located at one side of the kiln, a radial flue leading from the central part of the kiln through its base into the stack, a transverse flue opening into the inner end of the radial flue and provided at the ends with furnaces, floor flues arranged above and parallel with the radial flue and leading into the upper part of the transverse flue, an open-work floor over said floor flues, and an auxiliary furnace opening into the lower part of the stack.

In witness whereof I hereto affix my signature in presence of two witnesses.

ANTON VOGT.

Witnesses:

CHRISTIAN JOHNSON,
DAISY FRANCIS.
